CLAIM

The ornamental design for a modular pack shipping carton, substantially as shown.

DESCRIPTION

FIG. 1 is a perspective view of our modular pack shipping carton;

FIG. 2 is a front elevational view of our modular pack shipping carton;

FIG. 3 is a side elevational view of our modular pack shipping carton;

FIG. 4 is a top view of our modular pack shipping carton; and,

FIG. 5 is a bottom view of our modular pack shipping carton.

The portions of the modular pack shipping carton not shown in the drawings form no part of the claimed design.
